NEVIL GREENWELL, OF BETHLEHEM, PENNSYLVANIA, ASSIGNOR TO BETHLEHEM STEEL COMPANY.

DETONATING FUSE.

Application filed September 27, 1924. Serial No. 740,210.

The invention relates to detonating fuses for projectiles and it comprises means for insuring safety in handling the fused projectile and insuring the explosion of the 5 projectile at the proper moment when fired.

It should be understood that the high explosive constituting the bursting charge of projectiles is more or less inert under normal conditions and in order to obtain a complete 10 explosion it is necessary to provide a powerful detonating medium imbedded in the charge to initiate the explosion thereof. There are several well known substances 15 which are suitable for this purpose and of these substances, fulminate of mercury, is the most common in use. However, this latter substance is very sensitive to shock and the quantity which may be used with safety is limited. To cause the complete explosion 20 of a charge of a large calibre projectile, a comparatively large detonating element is required and the use of fulminate of mercury alone would be prohibitive. It is well known that when a column of this substance exceeds 25 certain proportions the shock occasioned by the discharge of the projectile from the gun is sufficient to cause the detonation thereof due to the inertia of the column of powder itself. To overcome this 30 danger a less sensitive explosive is interposed between the detonator and the projectile charge proper. The intermediate explosive substance while less sensitive than the detonating material used is, however, of a much higher order of explosive than the 35 material comprising the main charge of the projectile and serves to boost the wave of detonation from the detonating element and thereby effect a complete explosion of the 40 charge. Even though the size of the detonating element is reduced to a minimum sufficient to secure a high order detonation of the booster charge there is a certain element of danger in handling or due to shock 45 occasioned by discharge of the projectile from the gun causing a premature explosion. To avoid this danger it is usual to have the detonating element placed in a chamber 50 separate from the booster element of the fuse in such a manner that a premature explosion of the detonating element cannot be communicated to the main charge of the projectile.

An object of the present invention is to 55 employ in a fuse an extension spring, oper-

ated by the inertia of a movable member when the projectile is fired, to effect the movement of a detonator element of a fuse from its safety position into its active position within the booster charge. 60

A further object is to provide a device comprising an inertia member securely connected to one end of an extension spring, an anchoring means securely connected to the other end of the spring, said parts constituting a unitary structure which may be easily assembled in place in a fuse in assured correct relation to the coating parts comprising the fuse mechanism. 65

There are several known devices adapted to bring the detonating element into communication with the booster element after the projectile has been discharged from the gun and the acceleration of the projectile has ceased. Of these devices the most satisfactory are those which employ a compression spring to operate during the flight of the projectile and move the detonator element to its forward position within a pocket formed in the booster charge. However, 70 the use of compression springs as hitherto practiced for the purpose of effecting the movement of the detonator is unsatisfactory and unreliable, and particularly springs assembled in their compressed state. Compressed springs are disposed rearwardly of the detonating element and tend to urge the latter into its forward position but is prevented from this movement by means made inactive when the projectile is discharged 75 from the gun. The preferred means adopted for this purpose are centrifugal devices which serve the dual purpose of restraining the movement of the detonating element and at the same time function as a closure to 80 the passage communicating the safety chamber and the booster charge. Unless due precaution is taken the pressure of said compression spring against the centrifugal device will prevent the operation of the latter 85 and thus hinder the successful operation of the fuse. 90

Devices have hitherto been practiced which employ a compression spring positioned behind an inertia operated member and compressed by the latter when the projectile is discharged from the gun. Means are also provided to operatively connect said member to the detonator whereby the latter is moved 100 forward after the acceleration of the pro- 105

jectile has ceased. With the latter type of device difficulty is encountered when assembling the parts, particularly in quantity production, so that each part is operatively positioned with reference to the other. Furthermore, the sudden load imposed upon the compression spring causes the coils to buckle and distort and interfere with the correct functioning of the inertia member.

10 The present invention comprises generally a projectile fuse containing a booster charge and having a detonator element normally disposed in a safety chamber and separated from said charge by means of a centrifugally operated shutter, an inertia member slidably mounted in the safety chamber and restrained against rearward movement by means of an extension spring anchored at one end to the body of the fuse and secured 15 at the other end to the inertia member, and means whereby the latter member is operably connected to the detonator when moved to its rearmost position at the discharge of the projectile from the gun, so that the detonator will be moved forward to within the booster charge by said extension spring when acceleration of the projectile has ceased.

15 The novel features will be more fully understood from the following description and 20 claims taken with the drawings.

Fig. 1 is a longitudinal sectional view of a fuse embodying the invention in its normal or unarmed condition;

Fig. 2 is a similar view of the fuse showing 25 the various parts in the condition which it assumes when the projectile has moved a certain distance along the bore of the gun;

Fig. 3 is similar to Fig. 1, showing the various parts in the armed condition which 40 it assumes during the flight; and,

Fig. 4 is a cross sectional view on the lines IV—IV of Fig. 3.

Referring to the drawings, 10 indicates the body of the fuse which is of the ordinary 45 cylindrical form and threaded to engage a threaded opening centrally located in the base of a projectile. The fuse body is hollow, being closed at the rear end by a heavy cylindrical base 11 and at the forward end 50 by a screw plug 12. Threaded into the interior of the fuse toward the rear end of the cavity is a plug 13, which is bored from its front face to provide a seat for a block 14. The latter is retained in place by a plug 15 threaded in the plug 13. The front face of the plug 15 is centrally bored and recessed to receive a primer 16 which is supported by the block 14. The latter has a transverse 55 perforation 17 which contains a delay pellet 18 operating as a timing element and communicates with the primer through the flash ports 19. A passage 20 permits communication for fire from the delay pellet to pass to a magazine charge 21 between the block 14 and the bottom of the plug 13. The plug 13

has a central passage 21 through which the flash from the magazine charge passes for a purpose to be presently explained. Integral with the plug 13 is a reinforcing cylinder 22 extending forwardly within the 70 fuse body and is provided with an end flange fitting the interior wall of said body. At the forward end of the cylinder 22 is a fixed disc 23 which has a central opening to allow for the passage of a detonator hereinafter described. The portion of the fuse between the plug 13 and the disc 23 constitutes a strong safety chamber reinforced by the walls of the cylinder 22 to house said detonator in its 75 inactive position.

The disc 23 is provided with radial cavities in which are spring pressed bolts 24 which normally extend into the aforesaid central opening in the disc and prevent the passage of the detonator but which move outward during the flight of the projectile under the action of centrifugal force. Centrally located in the fuse cavity and surrounded by the cylinder 22 is a detonator 25 comprising a tube of relative small diameter filled with a detonating composition. The rear end of the detonator is threaded into a detonator holder 26 which is seated in the passage 21. The detonator holder has a tubular opening in line with the passage 21 90 through which fire may pass to ignite the composition in the tube. A cannelure groove is formed on the exterior of the holder 26 and retains a spring shoulder 27 for the purpose now to be described.

An annular plate 28 is gripped between the disc 23 and the cylinder 22 and has an annular groove formed in the face thereof to receive the end coil of an extension spring 29, which is threaded into position through an aperture in the plate provided for the purpose. The end of the spring is bent inwardly at right angles to constitute a detent which snaps into a pocket formed in the plate 28. An inertia member 30 is slidably mounted in the interior of the cylinder 22 and is centrally bored to slide over the detonator holder as illustrated in Fig. 2. A recess is formed in the face of the member 30 to receive the extension spring 29, the end coil of which is threaded through an aperture in the bottom wall of said member and securely locked in place in a similar manner as that employed to secure the opposite end coil of the spring to the plate 28. The inertia member 30 is grooved internally and the central bore is flared outward as indicated on the drawings. When the projectile is fired from a gun, the inertia of the member 30 causes relative longitudinal movement 110 between said member and the detonator holder, restrained by the extension spring 27, and the parts assume the position as shown in Fig. 2. The spring shoulder 27 is compressed by the passage of the inertia member 115 120 125 130

over the holder 26 and is reduced in diameter, however, when the aforementioned grooves in said member and holder register, the spring shoulder 27 returns to its original 5 condition and thereby locks the parts together.

In the chamber at the rear of the primer 15 there is arranged a percussion plunger having a firing pin, which is adapted to be 10 moved forward and fire the primer when the projectile is suddenly retarded in flight. This percussion device may be of any suitable form such for instance, as that shown in Patent No. 1,397,855, dated November 22, 15 1921. As illustrated in the drawing it comprises a cylindrical hammer body 31 on which is fixed an axially arranged firing pin 32, the point of which extends forward of the body. Surrounding the firing pin at its 20 forward end is a cylindrical guard 33 which is normally located in its forward position with its front surface flush with or forward of the firing pin point and held in this position by centrifugal bolts 34 which are normally 25 pressed into contact with the firing pin by springs. When these bolts are in their normal position as shown in Fig. 1, they prevent rearward movement of the guard 33. The bolts 34 operate in radial 30 openings in the hammer body and the guard is free to move rearwardly in an axial opening in the hammer body when the bolts are withdrawn.

In the chamber confined between the disc 35 23 and the plug 12 there is a booster charge of explosive material 35 having a central cavity 36 adapted to receive the detonator 25 when the latter is in its forward position as shown in Fig. 3. The forward end of the 40 detonator tube is of thicker metal than the balance of the tube and has a tapering wall 37 provided with a conical cavity in which there is a cone plug 38 for a purpose to be presently explained.

45 The operation is as follows: When the projectile is fired the member 30 moves relatively rearward under its inertia, restrained by the spring 29, passes over the detonator holder 26 and is locked therewith by means 50 of the spring shoulder 27 as heretofore described. The rotary movement of the projectile throws out the bolts 24, and when acceleration ceases, permits the spring 29 to move the detonator into the cavity 36 in the 55 booster charge. The bolts 34 in the percussion plunger are also thrown out permitting the rearward movement of the guard 33 on impact. The fuse is thus armed and on impact the firing pin strikes the primer and ignites the delay pellet which in turn, after 60 a predetermined interval of time, ignites the magazine charge 20 and the flame from the charge ignites the material in the detonator tube. This immediately detonates and explodes the booster charge which ruptures the

fuse and detonates the bursting charge of the projectile.

The operation of the safety devices embodying the fuse is as follows: The firing pin point is normally within the boundary of 70 the guard member and it cannot strike the primer if, for any reason, the plunger should move forward accidentally. If, in any way, the detonator 25 should be accidentally exploded during handling the projectile or due 75 to shock of discharge while in the gun, the explosion would drive the tapered gas plug 38 into the tapering end of the detonator tube spreading the latter and make it fit tight the opening in the disc 23. The end 80 of the detonator tube would be prevented from being blown forward by the bolts 24, the expanded gases not having strength sufficient to burst the walls of the body 10 reinforced by the cylinder 22. It will thus be 85 seen that while the described fuse is practically certain of operation when fired, it is provided with a safety device which makes it practically impossible for the booster charge to be detonated prematurely. 90

Having thus described the invention what is claimed as new and desired to be secured by Letters Patent is:

1. In a fuse for projectiles, the combination with a hollow fuse body, of a booster 95 charge in the forward part of the fuse formed with a receptacle for a detonator, a detonator normally in the rear of the booster charge and a disc in the rear of the booster charge having an opening through which the 100 detonator may pass, means adapted to be made inactive under centrifugal force for normally holding said detonator in place, an inertia member surrounding the detonator normally disconnected therefrom and adapted to be connected thereto when the projectile is discharged from the gun, a spring interposed between said inertia member and said disc, means to anchor one end of said spring to said inertia member, and means to 110 anchor the other end of said spring to said disc.

2. In a fuse for projectiles, the combination with a hollow fuse body, of a booster charge in the forward part of the fuse 115 formed with a receptacle for a detonator, a safety chamber in the rear of said booster charge, a wall between the latter and the safety chamber having a central opening coaxial with said receptacle, a detonator loosely 120 mounted in the safety chamber and supported in said opening at one end, an inertia member slidingly mounted in the safety chamber and resiliently connected to the fuse body, a resilient member mounted on the detonator adapted to engage said inertia member when the projectile is fired from a gun, and means made inactive by the rotation of the projectile for preventing the passage 125 of the detonator through said central open- 130

ing into the receptacle formed in the booster charge.

3. In a fuse for projectiles, the combination with a hollow fuse body divided into a plurality of chambers by walls of substantial thickness, of a booster charge in the forward chamber of the fuse formed with a receptacle for a detonator, a percussion device located in the rear chamber of the fuse, a detonator 10 loosely mounted in the intermediate chamber of the fuse, a primer mounted in the wall separating the last mentioned chambers, conduits adapted to convey the flash from the primer to the detonator, a central opening 15 in the wall between the intermediate chamber and said booster charge, means mounted in the latter wall adapted to normally prevent the passage of the detonator into said receptacle and to become inactive when the 20 projectile rotates, an inertia member slidingly mounted in the safety chamber, an extension spring intermediate said inertia member and the end wall of said chamber,

means to anchor one end of said spring to said end wall, means to anchor the other end of said spring to said inertia member, and means to establish a connection between the detonator and the inertia member on shock of discharge of the projectile from the gun. 25

4. In a fuse for projectiles, the combination of a fuse body having a safety chamber, of a detonator mounted in said chamber, an inertia member mounted in said chamber normally disconnected from the detonator, 30 an extension spring intermediate the inertia member, and the end wall of said chamber, means to anchor one end of said spring to said end wall, means to anchor the other end of said spring to said inertia member, and a groove formed in said member and 35 adapted to engage a spring shoulder mounted on the detonator when the projectile is discharged from a gun. 40

In testimony whereof I hereunto affix my signature this 23rd day of September 1924.

NEVIL GREENWELL.
